ATTORNEYS.

UNITED STATES PATENT OFFICE.

HARRY JAFFE, OF CHICAGO, ILLINOIS.

RADIATOR FOR INTERNAL-COMBUSTION ENGINES.

1,310,416.

Specification of Letters Patent.

Patented July 22, 1919.

Application filed July 16, 1918. Serial No. 245,160.

To all whom it may concern:

Be it known that I, HARRY JAFFE, a citizen of the United States, and a resident of the city of Chicago, in the county of Cook and State of Illinois, have invented a certain new and useful Improvement in Radiators; and I do hereby declare that the following description of my said invention, taken in connection with the accompanying sheet of drawing, forms a full, clear, and exact specification, which will enable others skilled in the art to which it appertains to make and use the same.

My invention relates generally to improvements in radiators for internal combustion engines; and it consists, essentially, in the novel and peculiar combination of parts and details of construction, as herein-after first fully set forth and described and 20 then pointed out in the claims.

The object of this invention is the production of a serviceable and highly efficient radiator for internal combustion engines, such as are employed in automobiles, traction engines, motor trucks, aeroplanes and the like, in which the motor cylinders are cooled by water surrounding the cylinders, which water is conducted to the radiator and is cooled therein by currents of air contacting 30 with the cooling surfaces of the radiator.

For this purpose, a radiator comprises a series of vertically disposed water tubes, connecting the upper and lower water chambers in said radiator structure, and a series of air conduits between each adjacent pair of water tubes. My invention is especially directed to the latter part of the radiator; and is fully illustrated in the drawings forming a part of this specification, and in which Figure 1 is a front elevation of fragments of a radiator, the figure being rather diagrammatic, to convey an idea of the appearance of the cellular structure of the radiator, and not illustrative of the specific details of construction disclosed in other figures. Fig. 2 is a vertical transverse section drawn on a magnified scale, the section being on line 2-2 of Fig. 1. Fig. 3 is a similar view disclosing a slight modification of my invention. Fig. 4 is a plan of a fragment of a strip of sheet metal formed to comprise a part of this structure, and Fig. 5 is an edge view of the same. Fig. 6 is an edge view, and Fig. 7 is a plan view of the filler strip 55 employed in the air spaces of the radiator.

Fig. 8 is a plan view of this latter strip prior to, or while, being formed as shown in Figs. 6 and 7. Fig. 9 is a diagrammatic view of a radiator core in which the cellular structure is secured to top and bottom plates, 60 which structure is soldered into the openings in the radiator casing. Fig. 10 is a plan view of the same. Fig. 11 is a detail view of a small portion of this filler strip, showing fins which project into the air 65 spaces to aid in the cooling process.

Like parts are designated by the same characters and symbols of reference in all the various figures.

A, in the drawings designates the casing 70 of a radiator, which casing may be of any desired or known shape or configuration, the one illustrated being of a well-known manufacturer of automobiles.

In the face, and the back wall of this casing there are large openings 12, through which the cellular core B is passed, and to which walls the core is thoroughly soldered. This core comprises a series of units C, each of which is formed of a strip, or strips of 80 sheet metal, as shown detached in Figs. 4 and 5, said strips being of proper width and length to correspond to the width and height of the core. This strip is crimped or corrugated transversely, the angles of the crimps 85 13, forming substantially two sides of a hexagon at the outer margins of this strip, while the intervening crimps between the marginal crimps are of a lesser altitude, so that when two of these strips are placed face 90 to back with the outer crimps in contact, there is formed between them a narrow passage D, which constitutes the water tube in the core. In the preferred embodiment of my invention, this crimped strip or ribbon is 95 made somewhat longer than twice the height of the core, it being bent and turned upon itself as shown at 15, Fig. 2, so that the crimps or corrugations point in opposite directions, and spaced apart to form between 100 them an air conduit E. The complete core is made up of a multiplicity of these units so that there is in each unit an air space E, and between adjacent units a water tube D, as clearly shown in Fig. 2. The crimps between the marginal crimping 13 may be angular, as shown at 14 in Figs. 4 and 5, or they may be curved, as illustrated at 14^a, in Fig. 3, the function of the crimps or corrugations being the same in either case.

In the air spaces there are located filler strips F, illustrated detached in Figs. 6, 7, 8, and 11; each of said filler strips being formed of a ribbon of sheet metal, shown flat in Fig. 5 8. This strip F is of a width corresponding to that of the strip forming the water tubes; and this strip F is bent or formed in a peculiar manner. It has, pointing in opposing directions, a series of angular members 16, the angularity of which approximates the angularity of the unit strips between its marginal crimps 13, and horizontally disposed members 17, so that when the formed filler strip F is placed into the air 10 spaces E, one of the angular members 16 contacts with the corresponding crimp 14 of one wall of the water tube. It is then formed to cross over so that its portion 17 is horizontally disposed and reaches to the adjacent wall of the unit, and follows the crimped portion thereof and then again crossed over to the first-mentioned wall; and this crossing back and forth continues through the entire height of the unit. It 15 will now be noted that one of the unit walls forms a series of two members of a hexagon and the opposing wall forms two complementary members thereof, while the cross bars 17 complete the hexagonal contour of 20 the cells.

In the longitudinal margins of the filler strip F there are a series of notches or excisions 18, of predetermined spacing so that when the strip is bent along the dotted lines 25 19, Fig. 8, to form a completed filler, these notches 18 will be in the angular portions 16 of this strip. It follows that this strip, by its horizontal portions divides the air space into a corresponding number of air 30 conduits, approximately hexagonal in transverse contour; and that owing to the notches 18 in the filler strip, the angular portion thereof prevents contact at its marginal edges with the corresponding marginal edges 35 of the unit members, except at the narrow portions 20 between said notches. The object of thus notching the filler strip is principally to save solder in the process of uniting the parts. Thus when a core has 40 been assembled, it is dipped with its face into a bath of liquid solder to a depth of approximately $\frac{1}{4}$ of an inch; and this solder will coat and adhere to all of the metallic surfaces thus immersed into the solder in 45 addition to entering the joints of the parts to be united. The coating of these exposed surfaces is practically a waste of solder which cannot be avoided, so that by notching the filler strips as described, a part of 50 the metal that would otherwise be tinned, is removed. This may appear at first sight to be a small matter of saving solder, but when it is considered that there are a large number of units in each core, and the large 55 number of radiators manufactured, this 60 65

saving of solder, amounting to probably one pound in each core, is quite an item in the cost of manufacturing radiator cores.

The object of the filler strips in the air spaces is to increase the cooling surfaces of the core by transmitting the cooling influence of the filler strips to the walls of the units, or in other words, to abstract heat from these walls.

In some instances it is advisable to form the units with single strips without the bends 15 therein, and to secure the ends thereof to plates 21, having slotted apertures for the reception of these ends, a construction preferred by some manufacturers of motor vehicles, to the one heretofore described.

In order to increase the cooling efficiency of the fillers, I provide the same with a multiplicity of incisions 22, Figs. 2, 8, and 11; and bend the portions between these incisions, as shown in Figs. 2 and 11 at 23, which portions project into the air conduits, and are, therefore, directly affected by the air passing through the conduits. Any number 90 of these elements 23 may be provided to obtain the desired result.

I have hereinbefore described the preferred embodiment of my invention, but I desire it to be understood that minor details 95 may be changed, and parts omitted without departing from the scope of my invention as defined in the subjoined claims.

Having thus fully described my invention, I claim as new, and desire to secure to myself by Letters Patent of the United States—

1. A radiator of the nature described, including a casing, and a cellular core, said core comprising a series of vertically disposed water tubes, and a series of air spaces 105 between adjacent water tubes, said water tubes having V-crimped walls, there being between adjacent water tubes an air space, and in each air space a single filler strip, said filler strip having crimped members 110 contacting alternately with one wall, and then with the opposing wall of said water tubes, and horizontal members contacting with both walls thereof, there being in the filler strips marginal notches in the crimped 115 portion thereof, said walls of the water tubes and the filler strip between adjacent water tubes affording the hexagonal, cellular, structure.

2. In a radiator core of the cellular type, 120 having water tubes and air spaces between the water tubes, a filler for the air spaces, said filler being a strip of sheet metal, there being in the marginal edges of said strip spaced apart notches, said strip being bent 125 and rebent so that the portions between the notches form horizontally disposed separating bars to divide said air space into a series of horizontal conduits, there being in said strip approximately medially of its 130

width a series of incisions, said incisions being in those portions of the filler strip which, after the strip has been bent and rebent, contact with opposing walls of the 5 water tubes, the portions of said strip produced by said incisions being bent to project into said conduits.

3. In a radiator of the nature described, a water tube, said water tube consisting of 10 two strips of sheet metal, said strips being continuously crimped along their longitudinal margins, each crimp forming two members or sides of a regular hexagon, said strips being also crimped between the marginal crimps and in the same direction, but the medial crimps being of lesser altitude than the marginal crimps to form when these two strips are placed face to back with the marginal crimps in contact, a narrow 15 passage, said passage having the contour of the medial crimps of said strip, there being in the radiator between each adjacent pair of water tubes a single filler strip, said 20 filler strip being a sheet metal ribbon having

a series of bent portions, said ribbon being 25 vertically bent to afford two angularly disposed members forming two sides of a regular hexagon, then bent to afford a horizontally disposed cross bar, then again vertically bent to afford two angularly disposed 30 members forming again two sides of a regular hexagon but in a direction opposed to the first-mentioned angularly disposed members, which members contact with two sides of the crimps in the walls of one of 35 the water tubes, the other angularly disposed members of the filler strip contacting with two sides of the crimps in the walls of the adjacent water tubes, whereby every alternate crimp in the water tubes is reinforced by the angularly disposed vertical crimped portions of the filler strip, there being in the longitudinal margins of said angular portions of the filler strip notches 40 for the object specified.

In testimony that I claim the foregoing as my invention, I have hereunto set my hand.

HARRY JAFFE.
